T. C. LENNY

BRUSH

Filed Feb. 16, 1926

FIG. 2

FIG. 3

Thomas C. Lenny
Inventor

Attorney

By Herbert E. Smith

UNITED STATES PATENT OFFICE.

THOMAS C. LENNY, OF OPPORTUNITY, WASHINGTON.

BRUSH.

Application filed February 16, 1926. Serial No. 88,541.

My present invention relates to improvements in brushes of the type used for floor and street sweeping, provided with a handle, and as a rule manipulated by the use of two hands of the sweeper. In such brushes the end of the handle is generally grasped by one hand, and in the control of the movement of the brush in connection with the hand which grasps in intermediate portion 10 of the handle, the hand grasping the free end of the handle usually moves relatively to the handle and in frictional contact therewith. This frictional engagement of the hand or rubbing on the handle causes 15 blisters and callous places to develop with consequent discomfort and inconvenience.

The primary object of my invention is the provision of means on the handle, and preferably located at its free end, which will 20 compensate for the relative movement of the hand and handle, prevent rubbing of the hand on the handle, and insure convenience in the operation or strokes of the brush when manipulated by the sweeper.

The invention consists essentially in providing an anti-friction, rotatable bearing member, as a head preferably located on the free end of the brush-handle and adapted to be grasped in the hand or fingers, and in 25 novel combinations and arrangements of parts in connection with this rotatable head as will hereinafter be more fully pointed out and claimed.

In the accompanying drawings I have illustrated one complete example of the physical embodiment of my invention wherein the parts are combined and arranged according to the best move I have thus far devised, together with a slight modification 30 thereof, showing the practical application of the principles of the invention.

Figure 1 is a perspective view of a brush embodying my invention.

Figure 2 is an enlarged sectional view of the bearing head showing its relation to the brush or broom handle.

Figure 3 is a perspective view of the ferrule or bearing sleeve used in the head.

Figure 4 is a sectional view showing a slight modification of the invention.

In carrying out the invention I utilize a brush or broom of the type illustrated in Figure 1 of the drawing in which the brush head 1 is equipped with the usual bristles 2 and located in position transversely of the

handle 3. The handle is secured in the brush head in any suitable manner and inclines upwardly therefrom as shown, with its free end 4 used as a bearing end for the hand grasp 5. The hand grasp is preferably 60 made in the shape of a spherical knob or rounded bearing head of convenient size to be grasped by the hand or by fingers and a thumb of the hand, and it is retained on the handle and adapted to rotate on an axis 65 forming a continuation of the longitudinal axis of the stationary handle.

The bearing head or knob is fashioned with a radial socket 6, and a smaller opening or bore 7 is formed as a continuation of 70 this socket. The socket as shown in the drawings is designed to fit over the end 4 of the handle, and the opening 7 is designed to accommodate a screw 8 that is threaded into the head 4 of the handle 3. The head 9 of 75 the screw is located in a countersunk opening of the hole 7 in order that it may not form an obstruction on the surface of the bearing head or knob, and to retain the knob on the end of the handle.

Between the screw head and the handle head, and encasing the smooth stem of the screw is located a metal ferrule or sleeve 10 which is fashioned at its inner end with a mushroom-shaped or tapered head 11, and 80 on the face of the end of the handle is located a perforated washer 12 through which the screw is passed. By the utilization of this construction the bearing head 5 is provided with a bearing which extends substantially through the head and includes the wall of the socket in engagement with the handle together with the ferrule or sleeve on the screw, and the bearing head is retained with stability on the handle but permitted to 85 freely turn thereon when grasped by the hand or fingers and thumb, as the broom or brush is manipulated.

The mushroom-shaped or tapered head 11 of the ferrule, which is resilient, permits the screw to be turned to bring the bearing head into such close relation to the handle as to prevent detachment therefrom, and at the same time permits the necessary rotary movement of the bearing head on the handle.

In some instances the handle 3^a of Figure 4 is of such a large size as to prevent attachment of the bearing head of the size shown in Figure 2. In such instance the end 4^a of 110

the handle 3^a is reduced and affords a bearing for the same bearing head or knob as used in Figure 2.

Having thus fully described my invention, 5 what I claim as new and desire to secure by Letters Patent is—

1. The combination with a brush handle of a knob having a socket and screw opening aligned therewith, a bearing ferrule in 10 said opening and having a flaring head, an attaching screw extending through said ferrule and its knob and secured in the handle.

2. The combination with a brush handle and an attaching screw secured thereto, of a knob having a socket and a screw opening 15 aligned therewith and fitted over the handle, a bearing ferrule encasing the attaching screw within said opening, a perforated washer on the end of the handle, and a mushroom-shaped resilient head on said ferrule engaging the washer. 20

In testimony whereof I affix my signature.

THOMAS C. LENNY.
